ABSTRACT OF THE DISCLOSURE

Hydrocarbons are subjected to thermal cracking to produce acetylene, at temperatures of 1000° C. and higher admixed with a diluent of aromatic hydrocarbon.

15

BACKGROUND OF INVENTION

The invention relates to an improved process for the production of acetylene by the cracking of hydrocarbons.

It is well known that acetylene may be obtained from hydrocarbons by providing, in the cracking zone, a temperature in the range of about 1000 to 1600° C., and even higher. However, at these temperatures, the rate of dissociation of acetylene into its elements, carbon and hydrogen is not negligible, and it is recommended that the hydrocarbons remain only for a very short period, within this cracking zone generally between 0.5 and a few tenths of milliseconds.

To prevent the decomposition of acetylene, the reduction of the period during which the cracked products are heated above 1000° C. has been attempted.

This may be made possible by providing a high gas feeding speed by maintaining a low partial pressure of hydrocarbons. The low partial pressure may be obtained by operating under a partial vacuum and/or by adding a sufficient quantity of gaseous diluent to the hydrocarbon. The use of a diluent also has the advantage of promoting the production of acetylene because the equilibrium

then has a high tendency to be displaced towards the right.

As gaseous diluent, water vapor is most frequently used on an industrial basis in an amount which may vary with respect to the amount of hydrocarbon, according to the conditions of pressure and dilution. However, under the usual conditions of temperature in acetylenic crackings, it has been found that part of the acetylene reacts with water vapor according to the reaction:

thus decreasing the quantity of acetylene which may be obtained. The speed of this secondary reaction rapidly increases when the temperature rises from 950 to 1400° C., and in the particular case of the cracking of ethane, at about 1400° C., H. S. Glick (7th International Symposium on Combustion, 1959, pp. 98-107) has shown that about 5% of the carbon content is converted into CO by the hydrolysis reaction of acetylene, in spite of the very short contact time, which is less than one millisecond.

Even though water vapor is a very useful industrial product, it is obvious that it does not really constitute an inert diluent and it causes serious acetylene losses.

Diluents other than water vapor have been proposed. Particularly, hydrogen, which is more chemically inert, has been suggested but it must be used in a cycle operation, which is difficult and costly since the gas is not easily condensed.

2

SUMMARY OF INVENTION

It has been found that it is possible to reduce the stay of the cracked gases in the cracking zone, so as to considerably decrease the decomposition of acetylene into its elements, while diluting the hydrocarbon content without causing the above disadvantages.

The invention is specifically directed to an improvement in acetylenic thermo-cracking processes in which the hydrocarbons submitted to the cracking operation are heated to temperatures higher or equal to 1000° C. and are diluted with one or more compounds selected from the aromatic hydrocarbons.

DESCRIPTION OF THE PREFERRED EMBODIMENTS

Among the aromatic hydrocarbons, benzene is preferred. However, any aromatic compound may be employed, for example, naphthalene, biphenyl, anthracene or the mixture of condensed products separated by cooling the gases resulting from the cracking process may also be used.

Surprisingly, it has been found that aromatic hydrocarbons are particularly suitable as diluents in thermal cracking. They all have in common excellent heat stability at temperatures of 1000° C. and higher.

Aromatic hydrocarbons are substantially chemically inert with respect to ethylene and acetylene under the residence time conditions required for the acetylenic cracking.

A fraction of the charge used in the acetylenic cracking produces benzene and other aromatic compounds which generally compensate for the eventual loss of diluent. Normally, the process does not require a benzene diluent supply.

By using an aromatic hydrocarbon diluent, it is possible to completely reduce the losses of acetylene which occur when the cracking process is carried out with water vapor as the diluent.

Furthermore, aromatic hydrocarbons may be separated readily by condensation. By recycling the diluent there is no inconvenient separation problems, such as those which occur when using hydrogen.

Advantageously, the diluent is benzene. Its low heat of vaporization does not require a very important amount of energy to transform it from the liquid state to the vapor state, when overheated under the cracking conditions.

The diluents according to the invention may be used with all acetylenic thermal crackings, since the heat required during the cracking operation may be supplied by means of hot gases, as in partial combustion or pilot flame crackings. Furthermore, when using Wulff type regeneration ovens or the like, the heat may be transmitted by contact with ceramic elements which have been previously heated.

When using regeneration ovens, it has been found that benzene has a favorable effect on thermal transfers. For example, by replacing water with benzene, under identical molar dilutions of the load, it is possible to double the heat transfer coefficients. This is made possible by replacing in the cracking zone, the laminar system with the turbulent system which has been found to have a favorable effect on the thermal transfer.

Generally, the molar ratio of diluent to hydrocarbon may be maintained between about 2/1 and 20/1, preferably between 4/1 and 12/1.

According to the invention, the nature of the hydrocarbon charge to be cracked has no influence on the diluent and the usual range of hydrocarbons from methane to light naphtha may be used.

For example, without limiting the object of the invention to particular cases, many comparative tests were carried out by cracking propane and n-pentane while diluting the hydrocarbon with benzene or with water vapor. The following examples, therefore are intended to illustrate the invention but must not be construed as limiting its scope in any manner whatsoever.

EXAMPLE 1

Propane diluted with benzene or with water vapor in a diluent/C₃H₈ molar ratio of 5/1 was fed to a cracking zone maintained at 1200° C., the mixture being under a total pressure of 0.5 atm.

The results obtained as a function of the residence time and the nature of the diluent appear in the following table. The rates of conversion into C₂H₂ and C₂H₄ are given with respect to the total number of carbon atoms present in the propane charge.

Rate of conversion of carbon	Diluent						
	Benzene			Water			
	C ₂ H ₄	C ₂ H ₂	C ₂ H ₄ +C ₂ H ₂	C ₂ H ₄	C ₂ H ₂	C ₂ H ₄ +C ₂ H ₂	
Residence in milliseconds.	10	0.42	0.18	0.60	0.42	0.16	0.58
	20	0.30	0.34	0.64	0.30	0.29	0.59
	30	0.20	0.43	0.63	0.20	0.33	0.53
	40	0.13	0.47	0.60	0.13	0.33	0.46
	50	0.08	0.47	0.55	0.08	0.31	0.39

With equal residence time, it has been found that the rate of conversion of propane into acetylene is always higher when it is diluted with benzene: the rate of conversion into ethylene is the same in the two cases; it does not depend on the nature of the diluent.

EXAMPLE 2

Under the same temperature and total pressure conditions as given in Example 1, n-pentane, diluted with benzene or with water vapor so that the diluent/C₅H₁₂ molar ratio is 11.1/1 was cracked.

The results also expressed as a carbon fraction of the converted C₅H₁₂ appear in the following table:

Rate of conversion of carbon	Diluent						
	Benzene			Water			
	C ₂ H ₄	C ₂ H ₂	C ₂ H ₄ +C ₂ H ₂	C ₂ H ₄	C ₂ H ₂	C ₂ H ₄ +C ₂ H ₂	
Residence in milliseconds.	10	0.40	0.19	0.59	0.40	0.17	0.57
	20	0.29	0.35	0.64	0.30	0.29	0.59
	30	0.19	0.44	0.63	0.19	0.33	0.52
	40	0.12	0.48	0.60	0.12	0.32	0.44
	50	0.08	0.49	0.57	0.08	0.30	0.38

Also in this case, the use of benzene has a marked increase in the production of acetylene.

What I claim and desire to secure by Letters Patent is:

1. In an acetylenic thermal cracking process in which a fluid paraffinic hydrocarbon submitted to a cracking operation is heated to a temperature equal to or higher than 1000° C., the improvement comprising carrying out said cracking with paraffinic hydrocarbon diluted with at least one aromatic hydrocarbon in a molar ratio of diluent to said paraffinic hydrocarbon of at least 2:1.

2. Process according to claim 1, in which said aromatic hydrocarbon is benzene.

3. Process according to claim 1 in which said aromatic hydrocarbon is selected from at least one member of the group consisting of a benzene, naphthalene, biphenyl, anthracene and a mixture of condensed compounds obtained by cooling the gases resulting from the cracking process.

4. Process according to claim 1 and the additional steps in which said aromatic hydrocarbon used as diluent is separated by condensation from the products of said cracking operation and is then recycled.

5. Process according to claim 1, in which the cracking operation is carried out by partial combustion.

6. Process according to claim 1, in which the cracking operation is carried out by means of a pilot flame.

7. Process according to claim 1 in which the cracking of said hydrocarbon is carried out in a regeneration oven.

8. Process according to claim 2, in which the cracking operation is carried out by partial combustion.

9. Process according to claim 2, in which the cracking operation is carried out by means of a pilot flame.

10. Process according to claim 2, in which the cracking of said hydrocarbon is carried out in a regeneration oven.

11. A process according to claim 1 in which said paraffinic hydrocarbon is in the range of methane to light naphtha.

12. Process according to claim 1 in which the molar ratio of diluent to paraffinic hydrocarbon is from about 2:1 to 20:1.

13. Process according to claim 1 in which the molar ratio of diluent to paraffinic hydrocarbon is from about 4:1 to about 12:1.
